UNITED STATES PATENT OFFICE

FRITZ LÄSSIG, OF CHEMNITZ, GERMANY, ASSIGNOR TO THE FIRM SCHUBERT & SALZER MASCHINENFABRIK AKTIENGESELLSCHAFT, OF CHEMNITZ, GERMANY

KNITTING MACHINE

Application filed January 29, 1930, Serial No. 424,304, and in Germany February 5, 1929.

My invention relates to hosiery machines and more especially to flat knitting frames.

It is an object of my invention to eliminate in these machines friction between the needle 5 and the presser head.

To this end I provide a movable presser head and means for moving the head and the needle bar at the same velocity and in the same direction while the presser bar is 10 in contact with the needles.

My invention offers important advantages with respect to the pressing and landing of the loops as compared with the existing machines. Heretofore, the needle and the 15 presser head were displaced with respect to each other while in contact, the closed needle head sliding along the presser head during the landing of the loop.

According to my invention the needle and 20 the presser head are moved in the same direction until they are separated during knocking-over. By these means friction between the needle and the presser head is eliminated altogether, preventing damage to 25 the needle and to the presser head. Particularly, breaking of the needle head and seizing of the needle head in the presser head are avoided. As friction is eliminated the speed of the machine may be greatly 30 increased as heating of the needles and the presser cannot now occur.

In the drawings affixed to this specification and forming part thereof a machine embodying my invention is illustrated diagrammatically by way of example.

In the drawings

Fig. 1 is a sectional elevation of the complete machine,

Fig. 2 is a sectional elevation of the knitting frame of the machine, drawn to a 40 larger scale,

Figs. 3 and 4 illustrate two relative positions of the presser head and the needle, and

Fig. 5 is a detail showing a rail for guiding the presser head.

Referring now to the drawings and first to Fig. 1, 13 is the frame of the machine, 14 is the main driving shaft which is mounted to rotate in the frame, 15 is a cam plate with 50 a single elevation 16, which is keyed on the

shaft 14, 6 is a rocking lever for operating the presser head 1, 17 is a roller at the lower end of the lever 6, and 17' is a spring which is anchored at a suitable point of the frame and with its free end is attached to the lower 55 end of the lever 6 so as to hold the roller 17 permanently engaged with the cam plate 15.

The lever 6 is keyed on a shaft 4. 5 is a lever which is also keyed on the shaft 4 and serves for reciprocating the frame 3 of the 60 presser head 1. The presser head 1 is divided or comb-shaped in the usual manner for cooperation with the jack sinkers 10 and the knock-over jacks 11. 18 is a pin at the lower end of the frame 3 which is engaged 65 by a slotted eye 19 at the end of the lever 5.

12 is the knitting frame on which the presser head frame 3 is fitted to reciprocate under the action of the lever 5 and 2 is a bracket attached to the upper end of the 70 frame 3 in which the presser head 1 is secured by any suitable clamping means. In the present instance the presser head is subdivided into presser plates, one per needle, but it might also be a single bar. A rail 7 75 is preferably inserted in the frame 12 to act as a guide and wear-strip for the rear faces of the presser plates 1, the rail being preferably made of steel or other wear-resisting material. 80

9 is the needle bar with the needles 8. The needle bar is connected with the usual frame 20 which is fitted to rock about a pivot 21 while it is reciprocated vertically.

For sinking the parts are in the position 85 illustrated in Fig. 2. The presser plates 1 have been raised between the knock-over jacks 2 to within reach of the sinkers 10, while their rear faces slide on the rail 7.

Referring now to Fig. 3, the needle bar 9 90 with the needles 8 is lowered, while the presser plate 1 still is in the position illustrated in Fig. 2, closing the needle heads. When the needle bar 9 is lowered further for landing the loops, the lever 6 is rocked by the cam 16 and the lever 5 moves down the frame 3 at the same velocity as the needle bar 9, so that the presser plates 1 and the needle bar 9 descend in unison and at 95 the same velocity, without friction. When 100

the needles have completed their descent they are moved to the right from the position in Fig. 4 for knocking over, and are separated from the presser plates 1 which 5 now are returned into the initial position, Fig. 2, by the lever 5. After the looping operation has been completed the needles 8 are also returned into the initial position, Fig. 2.

It will be understood that frictional contact between the needles 8 and the presser plates 1 occurs only on the comparatively short distance required for closing the needle heads. Otherwise the needles and the presser plate either move in unison or are separated.

I wish it to be understood that I do not desire to be limited to the exact details of construction shown and described, for obvious modifications will occur to a person 20 skilled in the art.

In the claim affixed to this specification no selection of any particular modification of the invention is intended to the exclusion of other modifications thereof and the right to 25 subsequently make claim to any modification not covered by this claim is expressly reserved.

I claim:—

A flat hosiery machine comprising a 30 presser-head frame, a needle bar, needles in said bar, sinkers adapted to cooperate with said means, a divided presser plate in said frame for each needle and means for moving said frame and said needle bar at the 35 same velocity and in the same direction while the members of said divided presser plate are in contact with their respective needles.

In testimony whereof I affix my signature.

40 FRITZ LÄSSIG.
